UNITED STATES PATENT OFFICE.

EMMA V. MEEHAN, OF WASHINGTON, DISTRICT OF COLUMBIA.

WEAVING FRAME.

Application filed August 10, 1925. Serial No. 49,379.

To all whom it may concern:

Be it known that I, EMMA V. MEEHAN, a citizen of the United States, residing at the city of Washington, in the District of Columbia, have invented certain new and useful Improvements in Weaving Frames, of which the following is a specification.

This invention relates to a weaving frame, and more particularly for one intended for 10 domestic use, and adapted for use in making rugs or mats of strips of rags of different textile materials, known usually as rag carpets or rag rugs.

One of the objects of the invention is to 15 provide a light and durable frame which may be readily manipulated to present the work in most convenient and comfortable position and provide it for readily operable means to feed and guide the "warp" cords 20 or threads, and hold them in properly spaced position in the weaving or laying operation, as well as to provide means for winding the warp off the warp roll at the proper time as the making of the rug progresses, and to 25 lock said roll against retrograde movement when enough warp has been fed for the time being.

A further object is to provide means for 30 conveniently winding or taking up and getting out of the way on one end of the frame, the completed portion of the rug or mat.

A still further object is to so construct the 35 frame that it may be readily folded to adapt it to occupy inconsiderable space, or for shipment.

A further purpose of the invention aside 40 from the structural characteristics of the device is to encourage artistic tendencies toward production of artistic household articles and to encourage thrift in domestic affairs.

In the drawings illustrating the invention—

Fig. 1 is a face view of the frame.

Fig. 2 is an edge view.

Fig. 3 is a cross section of either the top or bottom roll showing the manner of tying in the warp threads.

Fig. 4 is a detail perspective of one of the 50 guides for holding the said warp threads close to and parallel to the side pieces of the frame.

Fig. 5 is a plan view of a needle which may be employed.

55 Referring to the drawings, the numeral 1 designates a stand or support for the frame.

This may be of any suitable material, such as wood, or stamped metal. It comprises in the main two side standards 3 and 4, and a top cross piece 5. The standards are provided 60 at the bottom with extended base pieces or feet 6.

The frame as indicated at 6' is rectangular and comprises side pieces 7 and 8, top piece 9 and bottom piece 10. Journalled near the top of the frame is the warp roll 11, which is provided with a series of axial openings 12, into which are tied in series the warp cords 13, which extend downwardly and pass through apertures 14 in a guide plate 15, suitably supported between the side pieces of the frame below the warp roll. Journalled in suitable bearings near the lower part of the frame is another roll 16, one end of which is provided with a squared extension 17, which is provided with a ratchet 18 engaged by a spring pressed pawl 19 to prevent retrograde movement of the roll when it has been rotated to wind the finished portion of the rug upon the roll, and to at the same time tighten the warp thread.

The roll 11 is journalled upon a shaft 20, which at one side of the frame is extended through the circular slot 21 in an arcuate bracket 22 rigidly secured to the standard 1 of the support. This shaft is provided with a disk 23 on one side of the standard 1, which is secured to the shaft, and on the outside of the standard, a washer 24 is provided. The 90 shaft is threaded for the reception of a wing nut 25 by which means the frame may be held adjusted in any suitable angular position so as to bring the working position of the material conveniently in front of the 95 operator.

To guide the side warp cords I provide a series of screw eyes 26 with their openings close to their shanks, as shown in Fig. 4, so that a direct lateral pull of the edge warp cords will not pull them out of the eyes, yet the opening will afford easy access of the cords to the eyes and permit their ready removal. I prefer to increase the number of cords at the edge of the frame, as indicated at *a*, in which four cords are shown, which when interlaced with the "weft" or strip of rag or textile material will form in effect a single cord or core, thus forming a strong and durable edge for the rug or mat.

100 Preferably the next warp cord toward the center of the frame, indicated at *b*, is of

three strands or cords, and these cords may be diminished in number toward the center until a cord comprising a single strand is presented. These warp cords will be in practice made of as many strands as found necessary or expedient, diminishing from the outer edge toward the center.

The support is preferably made of two sections and hinged together by a hinge 27, 10 and on the edge of the piece opposite the hinge, may be provided two similar brackets 28, one on each section, to receive a bolt 29 by which, obviously, the sections of the frame are kept in alignment when the 15 device is in working position. Preferably the bracket 22 is secured to the standard 1 by screws 30, which may be readily removed so that the bracket may be taken off the standard when it is desired to fold the 20 frame. It is also desirable to make the frame in two sections, hinged precisely as the support 1, and hinged on the same line so that they may be folded simultaneously in the same general direction.

25 It will be noted that the swinging frame is not journalled centrally between the standards 3 and 4 of the support, but a little to one side. This is for the purpose of gaining ready access to the end of the journal of the lower roller to conveniently apply a wrench or key for tightening the warp threads and for rolling the finished part of the rug or mat upon said roller.

In operation, the top roll 11 is equipped 35 with a length of warp cord, according to the length of the rug or mat to be made. These cords, as before intimated, are taken down through the opening in the guide plate 15 in suitable groups, and are tied into the 40 roll 16, when the rolls are both rotated until the warp is perfectly tight, when the rolls are fixed. Then with a suitable needle the strips of textile material are woven into and out of and around the warp cords, according to the ingenuity of the worker, and 45 these strips are piled, one upon the other, in upward direction toward the center of the frame. When enough of the rug or mat has been completed to warrant rolling it 50 upon the lower roller, the wing nut 25 is loosened to permit the upper roller to turn, and the shaft of the lower roller is engaged by a suitable key or wrench, when the lower roller turns sufficiently to wind the completed portion of the mat or rug onto the 55 lower roller. Obviously at the same time, this will draw from the top roller a sufficient amount of warp cords, according to the fancy of the worker, to present another unfilled area to be filled in by the filler, or 60 strips of material. When this has been accomplished, the wing nut is again tightened, and also the lower roller is rotated until the warp threads are taut.

65 I preferably employ a suitable needle

such as is shown in Fig. 5. This is preferably made of twisted wire of suitable size so that it may be bent into various shapes to accommodate it for handling materials having different characteristics as to thickness, pliability, etc. 70

Claims:

1. A weaving frame for domestic use, comprising a support including side standards, a frame journalled in said standards, 75 a roll journalled in the top of the frame and a roll journalled in the bottom thereof, the journal of one of the rolls being extended beyond the side pieces of the frame, a bracket secured to the standard, and having a slot therein for the reception of said journal, means for securing the journal and thereby the frame in fixed position in the standard, and means for locking the lower roller in fixed position, substantially as and 80 for the purpose set forth. 85

2. A weaving frame for domestic use, comprising a support including side standards, a rectangular frame journalled in said standards, a roller journalled in the top of 90 the frame and adapted to carry the warp cords, a roller journalled in the lower part of the frame in which the lower ends of the warp cords are tied, means for locking the lower roller against rotation, means for locking the top roller in fixed position, and 95 means for guiding the warp threads.

3. A weaving frame for domestic use, comprising a support including side standards, a frame journalled in said standards, 100 a roller journalled in the upper part of the frame and adapted to carry the warp cords, a roller journalled in the bottom part of the frame into which the lower ends of the warp cords are tied, means for locking the lower roller in fixed position, and means 105 for locking the top roller in fixed position, said means also adapted to serve simultaneously to lock the frame in different angular relation to the support. 110

4. A weaving frame for domestic use, comprising a support including side standards, a frame journalled between said standards, a warp carrying roller journalled in the upper part of the frame, means for holding it in fixed position, a roller journalled in the lower part of the frame into which the lower ends of the warp cords are tied, means for locking said roller against rotation for the purpose set forth, a guide plate 115 supported in the frame below the top roller and provided with apertures for the passage of the warp cords, a series of open eyes secured to the side pieces of the frame through which the outer warp cords are adapted to pass, and whereby they are held in parallelism with the side pieces. 120 125

In testimony whereof I affix my signature.

EMMA V. MEEHAN
